LOADING BEAM

Albert H. Lathrop, Asheville, N. C., assignor to
 American Enka Corporation, Enka, N. C., a
 corporation of Delaware

Application August 7, 1942, Serial No. 454,035

2 Claims. (Cl. 214—10.5)

This application is a continuation-in-part of my application Ser. No. 441,207, filed April 30, 1942, and relates to the loading and transportation of yarn beams and the like. More particularly, the invention concerns an apparatus and a method for loading a large number of heavy spools or beams of yarn in a vehicle in such a way as to avoid shifting of the load in transit.

The invention is especially applicable to the loading and transportation of the type of heavy beams upon which rayon or other yarns are wound for shipment to manufacturers to be used, for example, for re-inforcing material in the manufacture of pneumatic tires and the like, and it is extremely important that the beams be loaded and maintained immobile during movement of the vehicle to thereby prevent damage to the yarn. These beams are suitable for transporting any type of yarn, but are particularly adapted for yarn of synthetic origin because of its delicate nature. Regardless of the denier yarn to be transported, relatively heavy packages are wound on each beam, the empty beams weighing several hundred pounds. A beam fully loaded with 1100 denier yarn may weigh between 1,000 and 1,200 pounds, and the loading of such a beam for shipment requires the exercise of considerable care to prevent injury to the yarn during transportation.

In the transportation of heavy yarn beams in a vehicle it is generally regarded as desirable, from the point of view of shipping economy, to load as many beams into the vehicle as may be consistent with safe transit. Due to the great weight and bulk of the loaded beams and the danger of shifting of the load with consequent injury to the yarn, the stacking of beams in superimposed tiers has been regarded as impractical, particularly in transportation by rail where severe shocks are frequently encountered in transit. Therefore, it has been customary to load beams in a single row, strongly braced, to insure safe delivery of the yarn. On the other hand, transportation of heavy yarn beams in superimposed tiers by motor truck has been proposed, and has been partially successful due to the fact that the load is subjected to only minor stresses in transit. One such proposal is described in U. S. Patent No. 2,144,600 to Koonce. However, Koonce does not provide means for preventing vertical shifting of the load or its components, nor are the chocks against the end beams sufficient to prevent longitudinal shifting under the stress normally encountered in rail transportation. Furthermore, each row of beams is treated as a separate entity, the upper row being maintained in contact with the lower row by its weight alone, and being therefore capable of independent displacement with respect thereto.

I have now found that due to the great weight

and bulk of the loaded beams, in order to insure maximum protection for the yarn wound upon the beams, under the severe stresses met with, particularly in rail transportation, the tiers of beams should be bound together into a compact unit and the whole so anchored to the vehicle body as to become a part thereof.

Therefore, an object of my invention is the provision of a method and means for loading heavy yarn beams in a vehicle in such a way that the load may be subjected to severe shocks in transit without incurring shifting of the load and consequent injury to the yarn.

Another object of the invention is the provision of a single and efficient mechanism for loading heavy yarn beams in a vehicle in tiers without danger of shifting of the load in transit.

A further object is the provision of a mechanism for loading heavy yarn beams in tiers as a single unit for transportation.

Other objects and advantages will appear from the following detailed description when read in conjunction with the accompanying drawings, wherein

Figure 1 is a sectional elevation of a portion of a vehicle, for example, a railroad freight car, showing a number of yarn beams loaded according to the present invention.

Figure 2 is a section taken on line 2—2 of Figure 1.

Figure 3 is a diagrammatic elevation, in partial section, of an entire freight car loaded according to the present invention.

Figure 4 is a detailed view of the shoe utilized in loading the second tier of beams.

Figure 5 shows a yarn beam in elevation and means for connecting the shoes, and

Figure 6 is a section taken along the line 6—6 of Figure 4.

In the drawings, the numeral 1 designates a freight car having a floor 2, side walls 3 and end walls 4. Affixed to the floor of the car and extending longitudinally thereof are T-shaped tracks 5, provided with vertically upstanding flanges 6 adapted to guide the yarn beams 7 as they are loaded, and prevent lateral shifting after the beams have been mounted in position.

Yarn beams 7 are of the usual type employed for transporting rayon and the like, and are provided with heads 8 and a shaft 9 which projects beyond the beam at each end. The beams placed on tracks 5 are connected by spacer bars 10 (see Figure 1) having openings bored in each end to receive the shafts 9 of adjacent yarn beams, said beams being similarly connected at opposite ends thereof. Between each pair of beams, vertical flanges 6 are provided with openings for the reception of bolts 11, screw-threaded at the ends to receive nuts 12. Tie bars 13 and 14 are connected at one end to the shafts of adjacent

beams, their other ends being affixed to bolts 11 and made fast by nuts 12. Thus all of the beams in the row are connected by spacer bars 10, and each beam is immobilized, that is, prevented from shifting laterally, longitudinally or vertically, by triangular braces comprising spacer bars 10 and tie bars 13 and 14 fastened to flange 6, as shown in Figure 1. Spacer bars 10 are preferably of equal size and length, the same being true of tie bars 13 and 14, so that the spacer bars are interchangeable and the tie bars are interchangeable, at will.

If desired, of course, instead of individual spacer bars 10, a single bar may be employed to connect an entire row of beams, said bar being provided with openings at spaced points to accommodate the beam shafts. It will likewise be readily understood that a number of tie bars 13 and 14 may be eliminated without seriously impairing the efficiency of the invention. For example, where the single spacer bar is utilized, all but two tie bars may be eliminated on each side of a row of beams, one tie bar being placed at each end of the row.

When loading the second tier, shoes 15 are mounted between adjacent beams of the first tier and the beams of the second tier are placed in the shoes by means of a suitable hoisting mechanism. Shoe 15 is a triangularly shaped member preferably made of metal, the sides 16, 17, and 18, of which are curved to conform to the shape of the spool head 8. Placed between pairs of beams in the bottom row, the sides 17 and 18 rest against the rims of adjacent beam heads. The rims of beams in the second tier are then cradled in side 16 and the shoes on opposite ends of each beam are connected and held in position by a rod 19 passed through openings 20 and screw-threaded at each end to receive nuts 21. The beam contacting faces of shoe 15 are provided with flanges 22 and 23 adapted to conform to the contour of the beam head 8 and prevent lateral shifting thereof with respect to the shoe.

Inasmuch as each beam in the second tier is placed between each pair of beams in the lower tier and rests thereupon, it is obvious that the latter pair of beams must be previously connected by spacer bars. Upon placement of the upper beam, the shaft 9 thereof is connected by tie bars 24 and 25 to the shafts of the adjacent beams in the lower tier, the three beams forming a triangle connected by a triangular brace consisting of spacer bar 10 and tie bars 24 and 25, the unit being anchored to the vehicle by means of tie bars 13 and 14. If possible, the length of spacer bars 10 is so chosen that the heads of adjacent beams are slightly spaced, for example, about an inch, so that the angle formed by spacer bar 10 and connected tie bars 24 and 25 describes an approximately equilateral triangle. Thus spacer bar 10 and tie bars 24 and 25 are then interchangeable at will. If desired, of course, the shafts of the upper tier of beams may be connected by spacer bars, and if a single spacer bar having openings at spaced points to accommodate the beam shafts is utilized, a number of tie bars 24 and 25 may be eliminated. In such case, for example, only one pair of tie bars 24 and 25 need be employed at each end of the row of beams.

Any suitable procedure for loading the second tier of beams may be adopted. However, since each beam of the second tier is placed between two beams in the lower tier, the two beams in the lower tier must be connected by spacer bars in order to brace them against the weight of the upper beam prior to the placement thereof. Thus the beams in both tiers are bound together as a balanced unit and the whole anchored to the vehicle in such a way as to prevent lateral, longitudinal and vertical movement thereof. It is, of course, within the purview of my invention to load any practical number of tiers in the same manner.

Having now described my invention in its preferred embodiment it should be understood that alterations may be made therein without departing from the spirit thereof. Therefore, the invention should be limited only by the scope of the appended claims.

What is claimed is:

1. Apparatus for loading a plurality of heavy yarn beams provided with projecting shafts, in at least two tiers in a vehicle, comprising a track having upstanding flanges to guide and prevent lateral displacement of the first tier of beams, rigid, unitary spacer bars of equal length connecting the said shafts of adjacent beams on each end thereof to prevent longitudinal movement of each beam with respect to each other and maintain each beam in fixed equi-spaced alignment, rigid unitary tie bars of equal length connecting each end of the shaft of each beam to the track at two points, except the shafts of the terminal beams which are connected to the track at only one point whereby lateral, longitudinal and vertical movement of the first tier of beams with respect to the vehicle is prevented, supporting means for each beam of the second tier carried by adjacent pairs of beams of the first tier, and a rigid connection between the shaft of each beam of the second tier and the shafts of the beams of the first tier whereby the entire load is rendered immobile during transit.

2. Apparatus for loading a plurality of heavy yarn beams provided with projecting shafts, in at least two tiers in a vehicle, comprising a track having upstanding flanges to guide and prevent lateral displacement of the first tier of beams, rigid, unitary spacer bars of equal length connecting the said shafts of adjacent beams on each end thereof to prevent longitudinal movement of each beam with respect to each other and maintain each beam in fixed equi-spaced alignment, rigid unitary tie bars of equal length connecting each end of the shaft of each beam to the track at two points, except the shafts of the terminal beams which are connected to the track at only one point whereby lateral, longitudinal and vertical movement of the first tier of beams with respect to the vehicle is prevented, supporting means for each beam of the second tier carried by adjacent pairs of beams of the first tier, and rigid unitary tie bars of the same length as the spacer bars connecting the shaft of each beam of the second tier to the shafts of its two supporting beams of the first tier whereby the entire load is rendered immobile during transit.

ALBERT H. LATHROP.
